UNITED STATES PATENT OFFICE

FRANZ JOSEF HERMANN, OF SINGEN, GERMANY

DUST REMOVING DEVICE FOR THRESHING MACHINES

Application filed September 4, 1928, Serial No. 303,731, and in Germany November 24, 1924.

This invention relates to a dust-removing device for threshing machines, by which the dust that arises in large quantities in the threshing machine, when working, is drawn out by suction so that the persons in charge are not inconvenienced thereby.

The object of the present invention is to simplify the construction of such dust-removing devices and thereby to cheapen the manufacture thereof. A further object is to minimize the weight of the apparatus and to reduce the space occupied by it while maintaining a high capacity.

According to the invention the dust-removing device is so constructed that it can draw in by suction not only the dust out of the threshing machine behind the threshing drum and over the straw shakers but also from other points, such for example as the short straw outlet. Furthermore by means of the invention a uniform suction effect is obtained over the entire breadth of the threshing machine, and by the characteristic construction of the aspirators an automatic cleaning thereof is obtained from the chaff, beards and so forth that are sucked in.

The accompanying drawings illustrate the invention in one constructional form and in its various details:—

30 Fig. 1 shows diagrammatically a threshing machine with a dust-removing device according to the invention.

Fig. 2 shows on a larger scale the portion of the dust-removing device mounted upon the threshing box.

Fig. 3 is a plan view similar to Fig. 2 but with the cover removed;

Fig. 4 shows a detail thereof;

Fig. 5 shows the dust-removing portion of the short-straw shaker and outlet;

Figs. 6 and 7 illustrate details of Fig. 5;

Fig. 8 shows a further constructional form of this aspirator;

Fig. 9 is a section on the line IX—IX in Fig. 8;

Fig. 10 shows a portion of the apparatus illustrated in Fig. 8 on an enlarged scale, partly in section and partly in outside elevation, and

Fig. 11 shows a portion of the apparatus illustrated in Fig. 1, partly broken away.

The new dust-removing device is composed of an upper casing 2 mounted upon the threshing box 1, a suction tube 3 which is connected with the casing 2 and which leads to any part of the threshing machine which it is desired to evacuate, such as the short-straw outlet 9, and of a suction device 4 connected with the tube 3. In the threshing box 1 the threshing drum 5 is supported in front with the threshing basket 6. In order to prevent grains of corn being thrown out of the threshing drum back to the threshing machine into the straw, a coarsely perforated plate or a wide-meshed sieve frame 7 is arranged behind the threshing drum, according to Fig. 1, and on the side of this perforated plate or sieve plate 7 which is inclined to the threshing drum 5 are provided plates 8 arranged like the slats of a Venetian blind, which catch the grains thrown out of the threshing basket. Through the wide-meshed sieve or coarsely perforated plate of the frame 7, the air laden with dust passes without hindrance, so that the current of suction air is in no way impeded thereby. Figure 11 shows a view of this sieve frame 7, with the slats 8. The chain 10 serves for adjusting this grain-catching device.

The suction casing 2 mounted upon the threshing box 1 is illustrated in its details in Figs. 2, 3 and 4. It consists of a box 11, preferably consisting of wood, extending over the breadth of the threshing machine, the bottom 12 of the box being provided with one or more circular apertures 13. Within the box are arranged a number of fan wheels 14 corresponding to the number of these apertures, the fan wheels being rotatable about vertical axes. The driving of these fan wheels is effected, according to Fig. 2, by a shaft 16 carrying a belt-pulley 15, through the medium of bevel transmission gears 17. According to the invention these fan wheels 14 are connected underneath with circular sieves 18, which fit accurately into the apertures 13 in the bottom 12 of the receptacle 11. Thus the sieves revolve at the same speed as the fan wheels, so that by the centrifugal action resulting therefrom the foreign bodies sucked on to the sieves are thrown outwards and consequently release themselves from the sieves.

In order also to enable particularly light bodies, such as portions of straw, stalk or the like to be released, there are arranged underneath the sieves special strippers which consist of short prongs 20 of resilient wire fitted on to wooden strips 19, as shown in Fig. 4. The distance between the sieves and these resilient wire prongs is so dimensioned as to correspond to about half the thickness of the straw stalks, but care should be taken that the spring wires do not come into contact with the sieve, because in consequence of the high speed or revolution of the sieves such contact would result in the sieves and the wire rods damaging or destroying one another, and might even produce sparks which would give rise to a danger of fire. The resilient wire rods are somewhat obliquely positioned according to Fig. 3, so that the portions adhering to the sieves are pushed on these resilient wire rods.

To the casing 2 of its box 11 is connected on the one hand a tube 21 extending to any desired distance and opening into the atmosphere, for carrying away the dust sucked in, and on the other hand the suction tube 3, which, as already mentioned, leads to a suction device 4, the object of which is to remove dust from the short-straw chamber for example. This suction device consists, according to Fig. 5, of a tube 22 which extends over the entire breadth of the threshing machine and which may according to Fig. 5 be rotated by a belt-pulley 23, of which the shaft 24 is supported in any convenient manner. The connection between the tube 22 and the suction tube 3 may then be constructed in a known manner, in such a way that the tube 22 is caused to rotate at the desired speed.

The tube 22 consists of wire gauze or of perforated or slotted sheet material, but the meshes or apertures in the tube must be so fine that only the dust-laden air can pass through them and not any larger particles of chaff, beards and the like. Now in order to obtain a uniform suction effect throughout the entire length of the tube 22, the interior of this tube is divided into individual chambers 26 by tubes 25 widening out like funnels towards one side. The tubes 25, of which only two are shown in the drawings, are inserted one into the other, and the funnel-like expansion of the tubes, which become gradually smaller in cross section, effects on the one hand a separation of the chambers 26 and on the other hand, with the second tube 25 inserted therein, such a narrowing of the cross section that the suction effect is distributed uniformly between the various chambers 26.

According to Figs. 6 and 7, in the funnel-like expansions of the tubes 25, guide plates 27 are also arranged concentrically with the inner tube, in order also to regulate and equalize the suction effect within the individual chambers.

In order to remove the chaff, beards and the like that settle on the sieve tube 22, according to Fig. 5, a brush 28 is provided, against which the sieve tube 22 bears, so that as it rotates it is freed by the brush from all adhering constituents.

If it gives rise to difficulties to rotate the sieve tube 22, according to Fig. 9, a stationary tube 29 may be used, which is only perforated in the upper half of its cross section, but may even be closed.

On the under side the suction tube 29 has a series of small nozzles or pipe unions 30, which may be connected with the tube in any convenient manner. These nozzles or unions may be either pressed in the tube 29, or, according to Fig. 10, may be riveted to it. Each of these nozzles 30 carries, by means of a short air-tight resilient connecting tube 31 preferably made of rubberized linen, a tubular body 32, which is closed by a bottom at its lower end. The connecting of the tubing 31 with the nozzle 30 and the body 32, may be effected in any convenient manner, for instance by means of bands 33 or the like. The sieve body may consist of a wire cylinder or of a cylinder of sheet material with perforations of suitable size and distribution.

The sieve bodies 32, suspended in a readily movable manner from the flexible tubes 31, hang vertically downwards when in a position of rest. Now when the threshing machine is being operated, the sieve bodies 32, in consequence of their resilient and readily movable suspension, are set in vibratory motion, thus preventing the settling of any rather large particles such as chaff, beards, or the like or else shaking off any particles of straw or the like that have already settled thereon. The short straw leaving the machine also raises and moves the sieve bodies, as shown in Fig. 9, the straw rubbing against the sieve bodies, so that the same success in cleaning the sieves is obtained as with brushes rubbing along the sieve surfaces. The sieve bodies 32 may of course be of some shape other than the tubular shape illustrated. They may be flattened, angular, or of any other suitable hollow form.

It may be observed that the sieve tube shown in Figs. 5 and 8 obviously admits of being used at some other part of the threshing machine. The suction box 2 may be replaced by a similar sieve tube, which must then in any case be equipped with a special suction blower. Similarly also the suction box may be connected to other parts of the threshing machine; and the sieve tubes according to Figs. 5 and 8 may be combined with one another in such a way that one is arranged at the top above the straw shakers, and the other in the short-straw chamber.

What I claim is:-

A dust-removing device for threshing machines, comprising a suction and sifting de-

vice, a sieve tube arranged at a part of the machine from which dust is to be removed, a suction pipe connecting the suction and sifting device with the sieve tube, interengaging tubular elements arranged co-axially in the sieve tube, the cross-sectional area of the tubular elements decreasing with their distance from the suction pipe, and a funnel-like expansion at the end of each tubular element remote from the suction pipe, the said expansion surrounding the inner end of an adjacent tubular element, and the free edges of the funnel-like expansions being close enough to the surface of the sieve tube to divide the sieve tube into a series of compartments.

In testimony whereof I have signed my name to this specification.

FRANZ JOSEF HERMANN.
